PEG FOR STRINGED INSTRUMENTS

Traugott Rohner, Evanston, Ill.

Application August 11, 1944, Serial No. 549,019

2 Claims. (Cl. 84—305)

1

This invention relates to improvements in tuning pegs for violins, cellos, and other stringed instruments, and has for its principal object to provide a more simple, inexpensive and relatively light device for producing an adjustable friction for tensioning the string while maintaining the outward appearance of a common tuning peg.

Many adjustable friction devices have been designed for a similar purpose, but they are generally of more or less complicated construction, with many parts, so as to be relatively costly and cumbersome, and at the same time having visible mechanical elements which are usually considered undesirable from an artistic viewpoint.

My invention may best be understood from the accompanying drawing, in which:

Figure 1 is a fragmentary plan view of the end of the peg box of a violin, and showing the end peg constructed in accordance with my invention.

Figure 2 is an enlarged view showing my improved peg unit removed from the violin.

Figure 3 is a longitudinal section of the peg unit illustrated in Figure 2, but showing the unit mounted in the peg box.

Figure 4 is a detail longitudinal section of the peg unit showing the several parts in partially disassembled relation.

Figure 5 is a sectional taken on line 5—5 of Figure 2.

Referring now to details of the embodiment of the invention illustrated in the drawings, the improved peg indicated generally at 10 is designed for mounting in the usual peg box 11 of a violin. As shown in Figure 1, the peg box includes two spaced side walls 12 and 13 which have aligned holes 14 and 15 respectively for receiving the tuning peg as usual.

The peg unit 12 consists of the several parts best seen in Figures 3 and 4. A flattened finger piece 16 having an integral shank 17 is made of a suitable light, yet strong material such as molded plastic or hard-wood. The finger piece is formed with an axially extending opening therethrough in the form of a polygonal section 18 extending the full length of the shank 17 and therebeyond, where it merges into an annular bore 19 at the outer end of the finger piece 16.

In the form shown herein, the polygonal sectioned opening 18 is substantially square in cross section as shown in Figure 5.

A spindle 20, preferably of metal, has a non-cylindrical outer end portion 21 which fits telescopically into a correspondingly non-cylindrical opening 18 of the finger piece, a relatively short intermediate annular portion 22, merging into an

enlarged collar 23 having an outwardly-tapering frusto-conical surface 24, and a reduced cylindrical inner end portion 25 of approximately the same diameter as the intermediate annular portion 22.

A cylindrical sleeve 26, preferably made of light material similar to that used in finger piece 16, may be fixed on the inner end portion 25 of the spindle 20, as by a pin 27, to form the winding spool for the violin string (not shown) the end of which is inserted as usual through a hole 28 in the said spool.

A friction bushing 30, made of suitable semi-yieldable material such as plastic surrounds the spindle in the area of the intermediate cylindrical section 22, and has a tapered inner face 31 corresponding with conical friction surface 24 of the collar 23. A fibre washer 32 may be inserted between the outer face of the bushing 30 and the inner end of the shank 17.

The conical surface 24 of spindle 20 is drawn into frictional engagement with the tapered surface 31 of bushing 30 by a hollow adjusting screw 33, fitted into the bore 19 at the outer end of the finger piece 16, and having threaded engagement with the reduced outer end extension 34 of the spindle 20, as shown in Figure 3.

The peg unit above described is assembled in the peg box in the following manner: The friction bushing 30 is disassembled from the unit, and is fixed tightly in the peg hole 15 of the peg box, as by gluing.

In practice, the diameters of the friction bushing 30 and the inner end 26 of the peg are such that the peg holes 14 and 15 may be reamed in one operation, to permit the bushing to fit closely in hole 15, while the inner end of the peg will fit loosely in the opposite hole 14.

When the bushing 30 is fixed in the peg box 40 as described, the parts are reassembled, as shown in Figure 3, and the screw 33 adjusted so as to give the desired amount of friction between the bushing 30 and the relatively rotatable parts of the peg with which it is engaged.

It will be observed that the spindle 20 is endwise slidable, but is non-rotatable in the finger piece, by reason of the squared shape of the end portion 21 of the spindle, and the receiving hole 18. It will be understood however, that these telescoping parts may be given any equivalent non-rotative or splined conformation for the same purpose.

The bushing 30 is frictionally engaged on one side by the conical surface 24 of the collar 23, and on the other side by the fibre washer 32,

abutting the inner end of the shank 17. Thus the area of frictional engagement is considerably increased by the provision of the conical surfaces within the limited space available. Wear due to friction will occur mainly in the fibre washer 32, but any such wear can be readily compensated for as required by adjustment of the tensioning screw 33.

Although I have shown and described certain embodiments of my invention, it will be understood that I do not wish to be limited to the exact construction shown and described, but that various changes and modifications may be made without departing from the spirit and scope of the invention as defined in the appended claims.

I claim:

1. A tuning peg for stringed instruments, a bushing adapted to be fixed in one wall of a peg box, and having a conical integral surface, a finger piece having an inner shank arranged for endwise abutting engagement with the proximate end of said bushing, a rotatable peg member comprising a spindle having its outer end arranged for rotatable bearing engagement with the other wall of the peg box, said spindle being provided with an intermediate integral tapered portion affording frictional engagement with the conical surface of said bushing and also having a portion extending through said bushing into non-rotative but endwise sliding engagement in said shank, and a screw rotatably mounted in the outer end of said finger piece having threaded engagement with the outer end of said spindle to adjust the friction effective between said bushing and said rotatable peg member.

35

2. A tuning peg for stringed instruments, a bushing adapted to be fixed in one wall of a peg box, and having a conical inner surface, a rotatable peg member comprising a finger piece having an integral shank arranged for endwise abutting engagement with the proximate end of said bushing and formed with an axial non-cylindrical opening therethrough, a spindle having its outer end arranged for rotatable bearing engagement with the other wall of the peg box, said spindle being provided with an intermediate integral tapered portion affording frictional engagement with the conical surface of the said bushing and also having a non-cylindrical portion extending through said bushing into non-rotatable but endwise sliding relation in the axial opening in said shank, and a screw rotatably mounted in said finger piece at the outer end of said axial opening, having threaded engagement with the outer end of said spindle, to adjust the friction effective between said bushing and said rotatable peg member.
